INVENTOR.

Milton F. Williams,
BY

H. M. Paisted,
ATTORNEY.

UNITED STATES PATENT OFFICE.

MILTON F. WILLIAMS, OF ST. LOUIS, MISSOURI, ASSIGNOR TO WILLIAMS PATENT CRUSHER & PULVERIZER CO., OF ST. LOUIS, MISSOURI, A CORPORATION OF MISSOURI.

FORGING-BLOCK.

1,305,854.

Specification of Letters Patent. Patented June 3, 1919.

Application filed December 18, 1918. Serial No. 267,336.

To all whom it may concern:

Be it known that I, MILTON F. WILLIAMS, a citizen of the United States, residing at St. Louis, State of Missouri, have invented 5 certain new and useful Improvements in Forging-Blocks, of which the following is a specification.

This invention relates to certain new and useful improvements in forging blocks for 10 pivoted rotary hammers, the peculiarities of which will be hereinafter described and claimed.

The object of my invention is to provide means for readily repointing and redressing 15 pivoted rotary hammers, particularly the style of hammer known as the "Ideal." This style consists of a flat bar, relatively much wider than thick, and curved forward at its operative end in a plane parallel to the 20 greatest dimension of the bar so as to produce a curved projecting point, and with the outer end beveled to 15 degrees or more from a squared end, to give the necessary clearance to the hammer. This hammer wears 25 off so that the operative point is rounding, and it is necessary to repoint it by heating and redressing the end and drawing forward the point again, by suitable means. Such means I have provided as shown in the accompanying drawing, on which like reference 30 letters indicate corresponding parts, and whereon Figure 1 represents a vertical sectional elevation through a block illustrating my invention; Fig. 2 a back view of the same; and Fig. 3, a front view of the same.

The letter A designates a base, flaring out from a standard or block B extending upward from said base and substantially rectangular, but with the back end preferably 40 chamfered to an inclination of about 28 degrees with the vertical as indicated in Fig. 1. The top is substantially horizontal, but may be slightly inclined downward toward the front. In the top and the inclined back end 45 of the standard or block, is a groove C rectangular at the bottom, and adapted to receive the lesser dimension of an Ideal hammer of the kind described. The groove is curved at the throat D where it changes

from the top to the back of the block, and a 50 wearing insert of comparatively hard steel E, is preferably inserted at this point, but may be dispensed with.

The bottom of the hammer being curved as indicated by the dotted lines in Fig. 1, is 55 provided with a curved nearly semi-circular socket block F at the bottom of said groove C, and this block is adjustable by means of shims G, or otherwise, so as to raise the socket when hammers of a shorter length 60 are being redressed; and vice versa.

In the manufacture of this style of hammer, the thickness of the hammer or its lesser dimension, likewise varies, and I have provided the groove C of width sufficient to 65 take the thickest hammer ordinarily redressed, and then adapt the said groove to a lesser width by means of an insert or shim H, Fig. 2, of variable thickness according to the thickness of the flat bar of the hammer 70 to be redressed.

The hammer to be repointed is first heated at the operative end and then laid in the groove C while the stock is drawn forward in the top groove over the curved throat, by 75 blows of a sledge hammer; the hammer being redressed is then taken from the groove and any excess width at the point is reduced, and any excess length of said point (measured from the center of the pivot hole at the bottom of the hammer,) is cut off by a chisel. The pivoted hammer is then retempered, and sharpened by grinding on an emery wheel.

I claim:

1. A forging block comprising a block having a substantially horizontal top, and a back that is inclined downward and backward from said top, and having a groove in said top and back,—the junction of the upper and back groove being curved,—and an insert of relatively harder material provided at said curve. 85

2. A forging block comprising a block substantially horizontal at the top and inclined downward and backward at the rear end, and having a groove extending along the top and back adapted for reception of a 95

pivoted hammer of the style described, and a socket block curved at the upper surface and fitting within said groove at the back and bottom, substantially as described.

5 3. A forging block comprising a block having the rear face inclined as described, a groove in said rear face and top, adapted to

receive a hammer of the class described, and a flat shim H inserted in said groove at the back, to adjust the width of said groove to 10 the thickness of the hammer being dressed.

In testimony whereof I have affixed my signature.

MILTON F. WILLIAMS.
